US0D1039079S

(12) **United States Design Patent** (10) **Patent No.:** **US D1,039,079 S**
(45) **Date of Patent:** **** Aug. 13, 2024**

(54) **WEIGHT**

- (71) Applicant: **Richard C. Petek**, Medina, OH (US)
(72) Inventor: **Richard C. Petek**, Medina, OH (US)
(**) Term: **15 Years**
(21) Appl. No.: **29/913,642**
(22) Filed: **Oct. 6, 2023**

Related U.S. Application Data

- (63) Continuation of application No. 29/779,933, filed on Apr. 21, 2021, now Pat. No. Des. 1,005,420.

(57) **CLAIM**

The ornamental design for a weight, as shown and described.

DESCRIPTION

FIG. 1 is a perspective view of a weight showing my new design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a perspective view of a weight showing my new design;
FIG. 9 is a front view thereof;
FIG. 10 is a rear view thereof;
FIG. 11 is a left side view thereof;
FIG. 12 is a right side view thereof;
FIG. 13 is a top view thereof;
FIG. 14 is a bottom view thereof;
FIG. 15 is a perspective view of a weight showing my new design;
FIG. 16 is a front view thereof;
FIG. 17 is a rear view thereof;
FIG. 18 is a left side view thereof;
FIG. 19 is a right side view thereof;
FIG. 20 is a top view thereof; and,
FIG. 21 is a bottom view thereof.
